DEPILATORY PAD

Ben Kapp, Chicago, Ill.

Application May 22, 1943, Serial No. 488,025

4 Claims. (Cl. 51—185)

This invention relates generally to devices for removing superfluous hair and particularly to a depilatory pad in which an abrasive is employed for removing the superfluous hair.

The use of sheeted abrasive materials, such as a fine grade of silicon carbide abrasive paper, has been extensively used for the removal of superfluous hair from the human body. Such abrasive pads have been provided in a variety of forms calculated to facilitate their manipulation. For example, the sheets of abrasive paper have been formed as a mitten, glove or a simple pad with a holding strip. But none of these arrangements is entirely satisfactory.

An object of the present invention is to provide an abrasive pad for the removal of superfluous hair in a form which will be conveniently manipulative and cheap to manufacture.

Other objects will become apparent to those skilled in the art when the following description is read in connection with the accompanying drawing, in which:

Figure 1 is a perspective view of a depilatory pad constructed in accordance with the present invention shown in relation to a convenient holding block;

Figure 2 is a diametrical sectional view of the depilatory pad shown in Figure 1;

Figure 3 is a plan view of a gripping and backing member utilized in accordance with the present invention as an alternative to the form shown in Figures 1 and 2;

Figure 4 is a plan view of a blank from which the gripping and backing member shown in Figure 3 may be made; and

Figure 5 is a diametrical sectional view of an embodiment of the present invention utilizing the gripping and backing member shown in Figure 3.

In accordance with the present invention, a sheet of abrasive material of the grade customarily used for removing superfluous hair is provided with a skirt of non-abrasive material which extends in a generally axial direction with reference to the plane of the sheet of abrasive material, so that the assembly constitutes a cup shaped article into the interior of which a suitable rigid holder may be inserted. Such a holder may take the form of a block of predetermined configuration: a nail brush, cake of soap, milk bottle, or any rigid article. When such a rigid holder is inserted within the cup shaped depilatory pad of the present invention, the skirted portion may be gripped against the rigid holder and held in sufficiently firm position to be easily

manipulated as by rubbing lightly over the hairy portions of the body in a manner well known to those skilled in the art.

While in the embodiments illustrated in the accompanying drawing the depilatory pad of the present invention is provided with a skirt of a generally frustro-conical shape, it is not to be understood that the invention is limited to cup-shaped members of this configuration, as it is obvious that the sides of the cup shaped member may extend at right angles to the abrasive face thereof, in which event the article will be generally cylindrically shaped. Furthermore, the circular form is not essential, as it will be understood that if a rigid holder of rectangular shape is preferred it will be advantageous to construct the cup shaped abrasive pad in a form which will generally accord with that of the holder to be used. Furthermore, if desired, a rigid holder of a fanciful shape may be provided and consequently the cup shaped member of the present invention should, in such cases, conform as nearly as may be to the contour of the fanciful holder.

Referring now to the drawing for an illustrative embodiment of the present invention, the cup shaped depilatory pad of the present invention comprises a sheet of abrasive material 1 which may be any of the well known sheeted abrasives recognized to be usable for the purpose of depilation. In the embodiment shown the abrasive sheet 1 is circular in contour and of a convenient size, as for example two inches in diameter. The back of the abrasive sheet 1 is adhesively secured to a gripping and manipulating backing member 2 which, in the embodiment shown, may be formed of heavy paper with its sides fluted as shown at 3. Such a cup shaped member may be formed from a flat blank, the excess substance toward the outer periphery being taken up in the process of formation as by flutes 3. The flutes 3 constitute a desirable attribute of the device as they reinforce the skirted portion of the cup shaped member 2.

Such a cup shaped member 2 having, on the exterior of its bottom surface, a sheet of abrasive material may be conveniently manipulated by means of a rigid holder 4 which, in the embodiment shown in the drawing, is a formed block having a lower portion 5 shaped in substantial conformity with the interior of the cup shaped member 2 and having its top portion rounded so as to be conveniently grasped in the hand with the fingers extending downwardly along the

side walls to an extent sufficient to engage the skirt portions of the cup shaped member 2 and press them into firm engagement with the portions 5 of block 4.

In the embodiment shown in Figures 1 and 2 the bottom of the cup shaped member 2 is integral with the skirted portion thereof, but it will be readily understood that such bottom portion may be formed of a separate piece—or indeed may be eliminated, save to the extent sufficient for connecting with the abrasive sheet 1 in cases where the physical characteristics of the backing sheet for the abrasive substance is sufficiently strong to sustain it during operation. Furthermore, a second sheet of abrasive material may be secured to the interior bottom of the cup shaped member 2 with its abrasive surface extending in the opposite direction from that of the sheet 1, in which case when the sheet 1 becomes worn the skirt 2 may be invaginated to expose the other sheet of abrasive material on the exterior for use.

In the embodiment shown in Figure 3 the manipulating member 6 is formed without fluting from a blank such as that shown in Figure 4, which may have its extremities 7 and 8 connected as shown at 9 to produce a frustro-conical cup shaped member having a discontinuous bottom. The bottom may be closed by a sheet of abrasive material 10 as shown in Figure 5, either with or without an auxiliary backing piece within the cup, or in lieu thereof a second sheet of abrasive material 11 arranged so that its abrasive surface faces opposite to that of sheet 10.

While for economy of manufacture it is desirable to form the cup shaped member 2 of heavy paper, those skilled in the art will readily realize that such a member may be formed of

fabric or other strong, flexible materials, it being understood that it is contemplated that the entire device be discarded when the abrasive surfaces become so worn that they are no longer effective to remove superfluous hair.

From the foregoing description those skilled in the art will understand the operation and advantages of the invention, and while two complete embodiments have been herein disclosed it is not to be understood that the invention is limited to the details thereof but that such embodiments are merely illustrative of the principles of the present invention, and that such modifications and variations thereof as do not depart from the scope of the appended claims are contemplated.

The invention having thus been described, what is claimed is:

1. A depilatory pad comprising, a sheet of abrasive material, and a skirt of non-abrasive material extending in a generally axial direction from said sheet of abrasive material.

2. A depilatory pad comprising, a cup shaped member of non-abrasive material, and a sheet of abrasive material secured to the exterior bottom of the cup shaped member.

3. A depilatory pad comprising, a paper cup having fluted sides and a flat bottom, and a film of abrasive substance on the bottom surface of the cup, the side walls of the cup being free of abrasive material.

4. A depilatory pad comprising, a cup shaped member of flexible material having a sheet of abrasive material affixed to the exterior of the bottom and another to the interior of the bottom thereof, the side walls of the member being free of abrasive material.
